UNITED STATES PATENT OFFICE.

THOMAS C. CAMPBELL, OF OWENSBORO, KENTUCKY, ASSIGNOR TO THE ANGLO-AMERICAN MILL COMPANY, OF OWENSBORO, KENTUCKY.

DRIVE MECHANISM FOR MILLS.

1,384,741.

Specification of Letters Patent. Patented July 19, 1921.

Application filed January 22, 1920. Serial No. 353,155.

To all whom it may concern:

Be it known that I, THOMAS C. CAMPBELL, a citizen of the United States, residing at Owensboro, in the county of Daviess and State of Kentucky, have invented new and useful Improvements in Drive Mechanism for Mills, of which the following is a specification.

This invention relates to an improved drive for mills and has as its object the provision of a mechanism which will overcome many of the present objections to mills due to their drive construction, all as hereinafter more in detail described.

In this description, it should here be stated that the invention is shown as applied to a mill of the character shown in the patent to A. R. Tattersall, 1,037,805, September 3, 1912, the mill therein shown being of the character in which the break and reduction rolls, by which the grain is reduced or ground up, and the centrifugal dressing devices are placed in close proximity to one another for short milling as distinguished from the long method of milling of some types of mills. It will be understood, however, that while the invention is herein shown and described as applied to this type of mill, its application is not so limited, but the same is adapted for use upon other types of mills.

One of the principal objections now had to mills of the type above referred to is the noise of their operation due to the meshing of the gears which drive the rolls and centrifugals, and it has long been desired to eliminate this noise and at the same time retain the desired differential between the movements of the various parts.

Another defect which users of mills of this type have noticed and have to contend with is the fact that it is often necessary to renew the break rolls which are of grooved construction, as these grooves often lose their depth and the roll must then be regrooved. When the user of the mill finds that these rolls are wearing, it is necessary for him to remove them from the mill and return the same to the factory for the renewal operations. It should be clear that when these rolls are regrooved their diameter is somewhat decreased, and when replaced in the mill their shafts take a position slightly nearer the shaft of the associated roll. When this operation is performed upon the rolls of a mill

such as is shown in the above referred to Tattersall patent, there must be an adjustment of the driving gears, one gear being located upon the shaft of each roll. It is also often necessary to change the gears to allow for the variation in the diameter of the worn rolls.

This invention has as its object the elimination of the above mentioned defects in mills by the substitution for gearing of a chain and sprocket drive. It has been attempted heretofore to eliminate a great number of the gears in these mills by the provision of a pulley and belt drive, but it has been found in practical use that due to the slippage of belts the proper differential cannot at all times be maintained. So far as I am aware I am the first to provide for mills a satisfactory chain and sprocket drive, and to eliminate the hereinbefore mentioned defects of these mills.

Referring to the accompanying drawings, wherein one embodiment of my invention is shown as applied to a particular type of mill,

Figure 1 is a sectional elevation of a portion of the rolls and centrifugals, and

Fig. 2 is an end elevational view of the mill.

Fig. 3 is a detail of one of the driving units.

As shown in the previously referred to patent to Tattersall, and as indicated in the accompanying drawings, the reference numerals 90 and 91 designate a two-chamber casing supported by a suitable frame. These casings are designed to be dust tight and in one, 90, are located the sets of break and reduction rolls and in the other, 91, the reels having therein beaters for dressing the stock delivered thereto by means of screw conveyers extending from the casing 90 at points beneath the pairs of break and reduction rolls.

In the accompanying drawings, the two rolls 1, 3, constitute the first pair of break rolls, the rolls 11, 17, the second pair of break rolls and the reduction rolls are indicated by the numerals 20, 23, and 29, 31.

Beneath each pair of break and reduction rolls is located a conveyer shaft 37 supported at one end in a bearing 37^a, and at its opposite end (not shown) in a similar bearing. Each of these shafts extends from the housing 90 into the housing 91 and within this latter housing carries spiders 38 which support beater blades 39 adapted to

beat up the stock within the usual reels 40. The manner in which the stock passes through such a mill as is shown in the accompanying drawings is all shown and described in the patent above referred to, and it is unnecessary to duplicate that description in this specification since the operation of such mills is well known in the art, and the present invention relates exclusively to 10 the drive mechanism shown in the accompanying drawings.

The drive mechanism comprises four distinct driving units A, B, C and D, each unit consisting of a pair of rolls and the associated conveyer shaft 37. As the drive for each of these units is identical, it will be necessary for the purposes of this description to describe in detail only one of these units. Upon the shaft extension 26 of each 20 of the upper, or slow, rolls 1, 11, 20 and 29 is located a sprocket 2, and directly below this sprocket upon the shaft extension 27 of each of the lower, or fast, rolls 3, 17, 23, and 31 a sprocket 4, both of the sprockets being 25 keyed to the shafts which as will be observed are supported in bearings 5. Adjacent each of the lower, or fast roll sprockets and keyed to a stub shaft 7 having a suitable bearing (not shown) upon the exterior of the housing 30 is an idler sprocket 6. As will be observed from an inspection of Fig. 2, the conveyer shaft 37 extends through the housing 90 and has keyed thereto sprockets 9 around which is looped a chain 10 whose 35 links are engaged in the manner shown in Figs. 1 and 3 with the sprockets of the two rolls and the idler sprocket. It will be observed that the sprockets of the rolls 1 and 3 are of different size to permit a differential 40 movement between these two rolls and by looping the chain 10 around the idler 6 the rollers 1 and 3 rotate in opposite directions.

Each of the driving units A, B, C and D, is transmitted power from a pulley 16 45 adapted to be driven by a belt from any suitable source of power and located upon the shaft 12 which is merely an extension of the shaft of the lower roll 17 of the second pair of break rolls. This shaft 12 carries a 50 sprocket 13 which is traversed by a chain 14 looped around sprockets 15 upon extensions of the conveyer shafts 37 and sprocket 16 upon shaft 27 of fast roll 31; and thus each 55 of the driving units may be transmitted power from the central shaft 12.

It should be understood, that while I have shown a particular embodiment of my invention and applied this embodiment to a particular type of mill, my invention is not 60 so limited in its scope, but is distinctly defined by the claims appended hereto, and by its relation to the prior art. From the above description, it will be seen that there is provided a mill drive which in addition to advantages such as economy of manufacture

and durability, possesses the distinct advantages hereinbefore mentioned, namely, an elimination of gearing and its attendant noise, a decrease of friction thus permitting the mill to be driven by less power and 70 thirdly the elimination of the numerous adjustments necessary with a gear drive.

Having thus described my invention what is claimed is:

1. In a self contained mill having a roll 75 section and a centrifugal section, pairs of rolls in said roll section, centrifugals in said centrifugal section, a conveyer adjacent each pair of rolls and means for actuating each member of said pairs of rolls in opposite directions and simultaneously actuating said conveyer, said means comprising sprockets associated with each roll and each conveyer and a chain engaging the sprockets of each pair of rollers and the sprocket of the adjacent conveyer.

2. In a mill of the class described having a roll section and a centrifugal section, a plurality of pairs of break rolls and reduction rolls in said roll section, a plurality of centrifugals in said centrifugal section for receiving the stock from said pairs of rolls, a conveyer adjacent each pair of rolls for transferring the stock to a centrifugal, a sprocket associated with each roll, a sprocket associated with each conveyer, a chain looped over the sprockets of each pair of rolls and the sprocket of the adjacent conveyer forming a plurality of driving units, and means for transmitting power to each of 100 said units.

3. In a self contained mill, a plurality of pairs of break and reduction rolls, a plurality of centrifugals, a conveyer for each pair of rolls for transferring the stock to a centrifugal, a sprocket connected to each roll, a sprocket connected to each conveyer, a chain looped over the sprockets of each pair of rolls and the sprocket of its adjacent conveyer forming a plurality of driving units, a main power shaft and a chain transmitting power from said shaft to each of 105 said driving units.

4. In a mill of the class described, a roll section, a centrifugal section, a plurality of 115 pairs of break and reduction rolls in said roll section, reels in said centrifugal section, a shaft adjacent each pair of rolls, a screw conveyer on each of said shafts, an extension of said shaft in each of said reels, stock 120 beater blades secured to said shaft extension and means for driving each member of said pairs of rolls in opposite directions and simultaneously driving said conveyer and beater shaft, said means comprising a 125 sprocket connected to each roll, a sprocket on each of said shafts, a chain looped over the sprockets of each pair of rolls and the sprocket of the adjacent shaft thereby forming a plurality of driving units, a central 130

power shaft and a chain for transmitting power from said shaft to each of said driving units.

5. In a mill of the class described, a roll section, a centrifugal section, a plurality of pairs of rolls in said roll section, a plurality of reels in said reel section, a shaft adjacent each pair of rolls and having a screw conveyer thereon, extensions of said shafts in 10 each of said reels, beater blades on the shaft extensions and means for driving said pairs of rolls and their adjacent conveyer and beater shafts, said means comprising a sprocket connected to each of said rolls, a 15 sprocket on each of said shafts, a chain looped over the sprockets of each pair of said rolls and the sprocket of the adjacent conveyer shaft thereby forming a plurality of driving units, a central power shaft, a 20 sprocket on said shaft and a chain looped over the sprocket of said power shaft and a sprocket in each of said driving units

whereby power is transmitted to each of the driving units.

6. In a self contained mill having a roll 25 section and a centrifugal section, pairs of rolls in said roll section, centrifugals in said centrifugal section, a conveyer adjacent said pairs of rolls and means for actuating each member of said pairs of rolls in opposite 30 directions and simultaneously actuating said conveyer, said means comprising sprockets associated with each roll and the conveyer and a chain engaging the sprockets of each pair of rollers, at least one of said chains 35 engaging the sprocket of the conveyer.

In testimony whereof I have hereunto set my hand in presence of two subscribing witnesses.
